UNITED STATES PATENT OFFICE.

WILLARD A. VAN BRUNT AND JOHN SCHAEFFER, OF HORICON, WISCONSIN, ASSIGNEES
TO THE VAN BRUNT MANUFACTURING COMPANY, OF HORICON, WISCONSIN, A COR-
PORATION OF WISCONSIN.

STOPPER FOR DISKS.

1,185,150.

Specification of Letters Patent. Patented May 30, 1916.

Application filed April 7, 1915. Serial No. 19,650.

To all whom it may concern:

Be it known that we, WILLARD A. VAN BRUNT and JOHN SCHAEFFER, citizens of the United States, residing at Horicon, in the county of Dodge and State of Wisconsin, have invented certain new and useful Improvements in Stoppers for Disks, of which the following is a specification.

This invention relates to a stopper for further opening disks and particularly to a stopper to be used in the disk bearings to protect the bearings against dust and foreign substances.

The main object of the invention is to arrange the parts so that the stopper will be effective in preventing the introduction of foreign substances into the bearing and at the same time present a device which can be easily and quickly removed.

In the drawings—Figure 1 is a vertical sectional view of a disk and its bearing, showing the improved stopper applied thereto. Fig. 2 is a side elevation of the disk stopper. Fig. 3 is an end view. Fig. 4 is a sectional view on the line $x-x$ of Fig. 2. Fig. 5 is a bottom plan view of a modification. Fig. 6 is a section on line 6—6 of Fig. 5.

Like parts are illustrated by similar characters of reference in the several views.

In Fig. 1 there is shown a specific form of bearing for a disk to which is applied the invention described herein. In that particular form of bearing illustrated in Fig. 1, the disk is indicated by 1. A housing 2 is secured to the concave face of the disk, a support for the disk is indicated by 3 and the drag bar is indicated by 4. The bearing block 5 is secured within the housing 2 by the bolt 6 in the usual and well known manner employed in disk construction. This particular form of bearing is more fully described in a prior Patent 659,881, issued March 19, 1900.

Referring to Figs. 1, 2, 3, and 4 the stopper for the bearing is formed with a circular cap 7 of substantially non-flexible material and a separate circular base 8 and between the base and cap there is clamped a spring member 9 by a rivet 11 and the free ends of said spring member are specifically formed to coöperate with the disk itself to cause the stopper to be securely held on the disk to prevent foreign substances entering the bearing and at the same time permit the stopper

to be readily removed from the disk. To this end, the free end of each arm is formed with a shoulder or apex 10 (see Fig. 4) and this shoulder 10 is so arranged in its relation to the cap 7 of the stopper and the wall of the disk that the edge of the opening in the disk will lie between the cap of the stopper and the spring member 9 as shown clearly in Fig. 1. The arms of the spring member converge inwardly from the shoulders as indicated in Figs. 3 and 4 and in inserting the spring member within the bearings, the free ends of the spring member will be forced inwardly, *i. e.*, toward the center of the disk until the shoulder or apex 10 of each of the two arms of the spring member pass the inner wall of the disk when the arms of the spring member will spring outwardly and engage the inner corners of the inner wall of the disk as shown in Fig. 1, thereby securely holding the stopper in proper position on the disk and the disk itself will extend between the flexible member 9 and cap portion 7 of the stopper.

In order to remove the stopper from the disk it is only necessary to insert something, such as the blade of a pen-knife, between the top portion of the stopper and the outer surface of the disk and thereupon a slight pressure will force the stopper out of its position and enable the stopper to be readily removed from the disk. The base 8 is formed with recesses 8' coinciding with the arms of the spring member to permit the inward yielding of the same in inserting or removing the plug.

In Figs. 5 and 6 are shown a modification in which the cap 12 and base portion 13 are cast in one integral piece, the base portion being formed with a recess 16 to receive the spring member 15, which is riveted to the cap 12 by the rivet 14. The construction and operation of this modified form is otherwise the same as shown in the preceding figures.

Having thus described our invention, we claim:

1. The combination with a disk formed with an opening, a stopper adapted to be inserted within the opening in said disk, comprising a cap of non-flexible material, and a spring member adapted to project within the opening formed in the disk, said spring member being spaced from the cap portion of the disk a distance equal to substantially

the thickness of the disk, whereby the disk will project within said space and the spring member contact against the inner edge of the disk and the cap member against the outer edge, substantially as specified.

2. The combination with a disk having a bearing and an opening in the disk extending into the bearing, of a stopper comprising a cap and a spring member secured thereto 10 having arms extending therefrom, each arm having a shoulder formed thereon and converging parts extending from said shoulders, the shoulder of each arm being adapted to spring into said opening beyond the inner 15 wall of the disk, whereby the spring member will clamp against the inner surface of the disk and the cap member clamped against the outer surface of the disk, substantially as specified.
- 20 3. The combination with a disk having an opening, of a stopper consisting of a cap portion and a base, said cap being of greater diameter than said opening and said base

formed to fit said opening, and spring arms secured to said parts arranged to project 25 through said opening, a portion of said arms normally lying in a plane so as to engage the inner wall of said disk adjacent the edge of the opening when the stopper is inserted.

4. The combination with a disk having an 30 opening, of a stopper consisting of a cap portion and a base, said cap being of greater diameter than said opening and said base formed to fit said opening, and spring arms secured to said parts arranged to project 35 through said opening, a portion thereof normally lying in a plane beyond the edge of the opening when the stopper is inserted, and recesses in said base portion to receive said spring member during the insertion of 40 said stopper.

In testimony whereof, we have hereunto set our hands this 22nd and 26th days of March 1915.

WILLARD A. VAN BRUNT.
JOHN SCHAEFFER.
